NORTH DAKOTA.

HOLDING DEVICE FOR GRAIN-BIN GATES.

Application filed October 14, 1922. Serial No. 594,498.

This invention relates to a grain bin for a grain elevator or a grain elevator leg and is particularly designed as a holding device for holding a gate in position, which gate is adapted to control the flow of grain from or into the bin or into the elevator leg. In grain elevator legs, an endless grain carrier is generally used comprising an endless belt having elevating buckets thereon and there is a gate at the front of the elevator leg for permitting the grain to flow from the front pit into said leg where it is received by the buckets. The main floor of the elevator is located some distance above the bottom of the elevator leg and the gate is customarily provided with an extension provided with handle means for opening or closing the gate, more or less, which handle means is manipulated from the elevator floor. It is very necessary that the flow of grain into the elevator leg be accurately regulated so that the elevator is not overloaded and yet is working efficiently. It is necessary to have some means to hold the gate in adjusted position which is positive in its action, else the flow of the grain will gradually move the gate toward closed position. Various devices, such as wooden wedges adapted to contact the sides of the gate and blocks placed under the operating handle, as well as ratchet wheels and gears have been used for this purpose, but such devices have been found to have many objections among which are slowness of operation and difficulty of adjustment, while the operator is manipulating the gate. It is desirable for the operator to take hold of the gate handles, as an experienced man can tell by having hold of the gate whether the grain is passing freely into the leg or whether there is some obstruction in the way, such as straw and other foreign matter. Such foreign matter tends to prevent the flow of grain into the elevator leg and also accumulates so as to prevent the proper closing of the gate when desired. If the operator can directly operate the gate he can easily free the passage of such foreign matter by a quick opening and closing movement of the gate. It is an object of this invention, therefore, to provide a gate holding means of extremely simple construction, which can be easily and quickly manipulated by the operator while he, at the same time, can take hold of the gate with one or both hands.

It is a further object of the invention to provide such a device comprising a lever pivoted and secured adjacent the gate having notch means thereon adapted to be engaged by a member movable with the gate. 60

More specifically, it is an object of this invention to provide such a holding device comprising a bell crank lever pivoted in a bracket secured to the elevator floor, which lever has an upwardly extending notched arm adapted to be engaged by a dog movable with the gate and having an outwardly projecting arm adapted to be operated by the foot of the operator, which lever is moved toward the dog or gate. 65 70

These and other objects and advantages of the invention will be fully set forth in the following description made in connection with the accompanying drawings in which like reference characters refer to the same parts throughout the different views, and in which

Fig. 1 is a vertical section through the grain bin and lower portion of the elevator leg showing the device of the invention in side elevation; 80

Fig. 2 is a vertical section taken on the line 2—2 of Fig. 1, as indicated by the arrows;

Fig. 3 is a horizontal section taken on the line 3—3 of Fig. 2, as indicated by the arrows; 85

Fig. 4 is a horizontal section taken on the line 4—4 of Fig. 2, as indicated by the arrows; 90

Fig. 5 is a view in side elevation of a portion of the holding device; and

Fig. 6 is a vertical section taken substantially on the line 6—6 of Fig. 5, as indicated by the arrows. 95

Referring to the drawings, the floor of the elevator is designated as 1, one of the grain pits below the same as 2, which has an opening in its lower side passing into the elevator leg 3, which opening is controlled by a vertically movable gate member 4 slidable in guides 5 at each side thereof. An endless belt 17 moves about suitable pulleys in said leg 3 and is equipped with elevator cups 18 adapted to receive and carry the grain upwardly in said leg. The said gate has an upwardly extending projection 6 provided with a handle means 7 at its upper end, which handle is disposed some distance above the floor 1. Said extension 100 105 110

is shown as moving in guide members 16 secured to the side of the elevator leg.

A U-shaped bracket 8 of simple construction is secured to the floor 1 adjacent the extension 6 and a lever is provided having a forked or bifurcated portion 9, the arms of which are disposed inside the arms of the bracket 8 and are pivoted thereto by a headed and nutted bolt 10. An arm 11 is formed on said lever and extends upwardly from the portion 9, being provided on its front side with notches or ratchet-shaped teeth 12. An arm 13 of said lever extends outwardly in substantially horizontal direction from the portion 9, which arm is curved somewhat downwardly, as shown in Figs. 1 and 5 and somewhat flattened on its outer end, as shown in Fig. 3. A coiled spring 14 encircles the bolt 10 and has one end bearing against the bracket 8 and its other end engaging the lever and tending to swing the same to move the arm 11 toward the gate extension 6. The said extension has secured thereto a dog or toothed member 15 having an outwardly projecting tooth adapted to engage one of the notches or teeth 12 on the arm 11.

When it is desired to close the gate 6, the operator can merely step on the end of the arm 13, thus swinging the teeth 12 out of line with the dog 15 and then push the gate downwardly by taking hold of the handle means 7. If it is desired to open the gate, the operator can stand squarely in front of the same and lift the gate by taking hold of the handle 7. He will at the same time step upon the lever arm 13, and when the gate is adjusted to the proper height, the arm 13 can be released so that the tooth 15 will engage one of the teeth 12. As the arm 11 is pressed toward the dog by the spring 14, the gate will thus be securely held in its adjusted position. If the operator wishes to quickly raise and

lower the gate one or more times to free the grain passage of any obstruction, this can be done by merely stepping on the arm 13 and swinging the arms 11 out of the path of the dog 15.

From the above description it is seen that applicant has provided an extremely simple and very efficient holding device for a grain gate. The gate can be locked almost instantly in its adjusted position and its locking operation does not necessitate any difficult or large number of movements by the operator. On the other hand, the locking means can be easily and quickly manipulated by the operator's foot while he controls the gate with his hands. The invention comprises very few parts which can be cheaply and ruggedly made and will be easily installed and very durable.

It will, of course, be understood that various changes may be made in the form, arrangement and details of the parts without departing from the scope of applicants' invention, which, generally stated, consists in the matter shown and described and set forth in the appended claim.

What is claimed is:

A holding device for a sliding panel, comprising a dog mountable on the panel, a U-shaped bracket mounted at the lower edge of the panel facing said dog, a bifurcated portion pivoted to said bracket, said portion having a substantially vertical arm with notches thereon facing said dog, one of said notches being engageable therewith, and a substantially horizontal arm for moving said notches out of engagement with said dog, and means for normally urging said notched arm towards said dog.

In testimony whereof we affix our signatures.

LOUIS H. PALMER.
FOREST W. PALMER.
